By William J. Jones,
Attorney

UNITED STATES PATENT OFFICE.

VINCENZO SANSEVIERE, OF BROOKLYN, NEW YORK.

CHALK-HOLDER.

1,049,152.

Specification of Letters Patent. Patented Dec. 31, 1912.

Application filed April 30, 1912. Serial No. 694,268.

To all whom it may concern:

Be it known that I, VINCENZO SANSEVIERE, a citizen of the United States, residing at Brooklyn, in the county of Kings 5 and State of New York, have invented certain new and useful Improvements in Chalk-Holders, of which the following is a specification.

My invention relates to improvements in chalk holders, particularly adapted for use 10 in chalking the tips of billiard and pool cues.

The object of the invention is to provide a chalk holder which may be locked in active 15 position to prevent surreptitious removal of the chalk.

To the accomplishment of the recited object and others subordinate therewith, the preferred embodiment of my invention resides 20 in that construction and arrangement of parts hereinafter described, illustrated in the accompanying drawings, and embraced within the scope of the appended claims.

25 In said drawings: Figure 1 is a perspective view of the chalk holder embodying my invention. Fig. 2 is a vertical sectional elevation of the device. Fig. 3 is a detail perspective view of the locking screw. Fig. 30 4 is a transverse sectional view taken along line 4—4 of Fig. 3, and Fig. 5 is a detail perspective view of one of the clamps partly broken away to more clearly show the construction.

35 Generally speaking, my invention involves a pair of clamps adapted to conform to the standard size of the blocks of chalk ordinarily used in playing pool and billiards, the said clamps having upwardly 40 extending shank portions which are hingedly connected together and otherwise arranged to form an inclosure for a coöperating screw designed to be adjusted to secure the desired engagement of the clamping 45 members with the chalk.

Referring more particularly to the drawings for a detail description of my invention the numerals 1 and 2 designate a pair of clamps provided at their lower edges 50 with teeth, as 3, and having vertically disposed angular flanges 4, one upon each end thereof. Each clamp has its upper portion bent inwardly as at 5, and these in turn merge into vertical shanks, as 6 and 7, 55 hingedly connected adjacent their lower extremities by means of the integrally formed

projections 8 and pins 9, while the upper extremities of the shanks are flexed inwardly upon opposite sides so that two projections 10 carried by the shank 6 interfit with 60 respect to a pair of projections 11 formed on the shank 7, and in this way present an inclosure, the function of which will be presently described. If desired the upper terminal of the shank 7 may be extended 65 beyond the plane of its flanges 11 to constitute a projection 7^A, which has an opening 7^B to facilitate hanging or suspending the complete holder from a spring or the like. 70

At a point approximately medially of the vertical extent of each shank there is provided a transverse instruck or ridge portion 12, and formed as a rigid part of the shank 7 is a horizontally disposed plate 13 having a screw-threaded opening 14 intended to receive the shank 15 of a screw 16, the body portion 17 of which has substantially the contour of an inverted frustum, a squared head 18 being disposed upon the 80 opposite side of the body 17 and adapted to be operated by means of a key, as 19.

The body portion 17, as clearly shown in Fig. 2 of the drawings, normally occupies a position intermediate the ridges 12 of the 85 shanks 6 and 7.

In practical operation, the shank 15 is unscrewed from the plate 14 by means of the key 19 until the body 17 disengages the ridges 12. This operation permits of the 90 upper extremities of the shanks 6 and 7 being contracted with a resultant expansion of the clamps or jaws 1 and 2. The block of chalk 20 is then inserted between the clamps and the hereinbefore described operation is reversed, and the body portion 17 of the screw being constrained downwardly in engagement with the ridges 12, thereby causing the clamps or jaws to be brought toward each other and in effective engagement with the opposite sides of the block of chalk. It will be noted that when the screw 105 has reached its lowermost position the head 18 thereof will be sufficiently below the upper extreme edges of the shanks 6 and 7 to preclude any possibility of the same being tampered with by inserting a pen-knife, or the like. It will also be noted that the block of chalk may be adjusted in any desired position with respect to the jaws 1 110 and 2, and this is considered an important feature, for as the chalk becomes worn it

usually assumes the form of a shell, the walls of which would quickly be broken were it not for the fact that the block can be moved outwardly to permit the teeth 3 5 to engage the chalk at different points.

It should be understood that in its broader aspect the invention comprehends the employment not only of the various means described, but of equivalent means for performing the recited functions. While the arrangement shown is thought at the present time to be preferable, it is desired to reserve the right to effect such modifications and variations thereof as may come fairly 10 15 within the scope of the appended claims.

What is claimed, is:—

1. In a chalk holder, the combination of a pair of jaws, each jaw having a shank portion, said shank portions being pivotally connected together, one of said shank portions having a rigid extension provided with an aperture, a screw adapted to operate in said aperture, and means coöperating with said screw for causing a closing of the jaws. 20
2. In a chalk holder, the combination of a pair of jaws, a shank carried by each jaw, said shanks being pivotally connected together and presenting an inclosure, and ver- 25

tically movable means for operating said jaws, the top of said means terminating 30 short of the top of said inclosure in active and inactive positions.

3. In a chalk holder, the combination of a pair of jaws, each jaw having shank portions pivotally connected together, one of 35 said shanks having a right angular extension below the top thereof, and means vertically movable through said extension and engageable with the shanks for closing the jaws. 40

4. In a chalk holder, the combination of a pair of jaws, said jaws having shank portions pivotally connected together, said shanks having a pair of oppositely disposed coöperating projections, one of said shanks 45 having a second projection lying in a plane at right angles to said first mentioned projections, and means movable through said second projection and engageable with the pair of projections for closing said jaws. 50

In testimony whereof I hereunto affix my signature in presence of two witnesses.

VINCENZO SANSEVIERE.
